UNITED STATES PATENT OFFICE.

ELLON S. HILL, OF NEW HAMPTON, NEW HAMPSHIRE, ASSIGNOR TO BOX BOARD PRODUCTS, INC., OF NEW YORK, N. Y., A CORPORATION OF NEW YORK.

BOX OR CARTON.

Application filed June 8, 1922. Serial No. 566,680.

To all whom it may concern:

Be it known that I, ELLON S. HILL, a citizen of the United States, residing at New Hampton, in the county of Belknap and State of New Hampshire, have invented new and useful Improvements in Boxes or Cartons, of which the following is a specification.

This invention relates to boxes or cartons made from paper-board, and has for its object to provide a box, the side walls of which are inexpensively stiffened and reinforced to resist crushing pressure exerted downward on the top of the box.

15 The invention is embodied in the improvements hereinafter described and claimed.

Of the accompanying drawings forming a part of this specification,—

20 Figure 1 is a plan view of a box blank embodying the invention.

Figure 2 is a perspective view of a box formed from the blank shown by Figure 1.

The same reference characters indicate 25 the same parts in all of the figures.

A box blank embodying the invention is preferably composed of a single one-piece body of paper-board, and two stiffening and reinforcing pieces. The body includes 30 a bottom portion 12, two side wall portions 13, having flaps 14 at their opposite ends, and two end wall portions 15. The body is creased or otherwise adapted to be bent along predetermined lines, as indicated by 35 dotted lines 16 in Figure 1. The reinforcing pieces 17, also preferably of paper-board, are glued to the side wall portions 13 while the body is flat, and are of substantially the same width as the portions 40 13, although they may be considerably shorter, as shown.

The operations of bending the thus completed blank on the lines 15, and of gluing the flaps 14 to the portions 15, form the box shown by Figure 2, the reinforcing pieces being on the inner side of the box wall, and extending from the bottom to the upper edge of the wall, so that the portions 13 are adapted to support a considerable

pressure from above, without being crushed or buckled.

The end wall portions 15 are correspondingly reinforced by the flaps 14, cemented to their inner sides.

The blank shown by Figure 1, constitutes 55 an article of manufacture, which may be supplied to a user, who converts it into the open box shown by Figure 2, the box being reinforced both at its side and end wall portions, so that the wall is adapted to support 60 a cover and pressure exerted thereon.

Owing to the fact that the reinforcing pieces 17 are of substantially the same width as the side wall portions 13, the lower edges of the reinforcing portions bear on the bottom portion 12, and their upper edges are flush with the upper edges of the side wall portions, in the completed box, as shown by Figure 2. The reinforcing pieces, therefore, constitute struts adapted to prevent 70 edgewise compression of the side wall portions by downward pressure thereon.

I claim:

1. As an article of manufacture, a foldable box or carton blank comprising a bottom portion, side and end wall portions extending from the corresponding edges of the bottom portion, each of said side portions being of one-piece construction, and reinforcing pieces secured to the side wall 75 portions at their mid length, said reinforcing pieces terminating a substantial distance short of the ends of the said side wall portions, whereby said reinforcing pieces constitute struts adapted to prevent edge-wise compression of the side wall portions by downward pressure on the upper edges thereof.

2. A paper box having side wall portions of one-piece construction devoid of folds or pleats, the mid-length portions of said side walls having separate reinforcing panels of paper stock adhesively secured thereto, said panels being of considerably less length than said walls.

In testimony whereof I have affixed my signature.

ELLON S. HILL.
